UNITED STATES PATENT OFFICE.

SENECA H. TROMANHAUSER, OF MINNEAPOLIS, MINNESOTA.

BUILDING WALL.

Application filed February 3, 1920. Serial No. 355,967.

To all whom it may concern:

Be it known that I, SENECA H. TROMANHAUSER, a citizen of the United States, and a resident of Minneapolis, county of Hennepin, State of Minnesota, have invented 5 certain new and useful Improvements in Building Walls, of which the following is a specification.

My invention relates to walls for dwelling houses and other buildings of a similar type and the object of the invention is to provide 10 a means for utilizing a concrete construction without additional metal reinforcing means which adds so much to the expense 15 and labor of building a concrete wall.

A further object is to provide a wall which will be fire and sound-proof and will also be insulated against the transmission of 20 moisture resulting from variations in the temperature to which the wall is exposed.

A further and particular object is to provide a wall construction which will be simple and inexpensive and at the same time be extremely strong and durable and may be 25 easily made to meet the artistic requirements of modern architecture.

The invention consists generally in providing a form, either wood or metal, as preferred, pouring the concrete therein and then 30 putting the finishing coat of plaster on the form which, after the concrete becomes set, forms a jacket or shell therefor.

Further the invention consists in various 35 constructions and combinations, all as hereinafter described and particularly pointed out in the claims.

In the accompanying drawings forming part of this specification,

Figure 1 is a horizontal sectional view 40 through a portion of a building wall embodying my invention,

Figure 2 is a vertical sectional view on the line 2—2 of Figure 1,

Figure 3 is a modified construction, showing 45 an air space on both sides of the concrete wall,

Figure 4 is a view corresponding to Figure 1, showing the invention applied to a metal form of construction,

Figure 5 is a vertical sectional view on the line 5—5 of Figure 4,

Figure 6 is a detail sectional view, showing 50 the manner of mounting the expanded metal lath or fabric on the wall or frame of the form,

Figure 7 is a similar view, showing an-

other means for holding the fabric on the form.

In the drawing, Figure 1, 2 represents the outer upright studs and 3 the inner opposite 60 studs secured to the outer studs by suitable means, such as the short transverse slats or lath 4 placed at suitable intervals, as indicated by dotted lines in Figure 2. The studs are placed the usual distance apart in wall 65 construction and are connected by lath 5, horizontally arranged between the studs. I prefer to place sheets of suitable building paper 6 which serve as a means to prevent the liquid concrete from flowing outwardly 70 between the cracks of the lath. Similar lath 5^a are secured to the inner vertical edges of the studs 2 and building paper 6^a may be interposed between these lath and the studs. The outer vertical faces of the studs 2 are 75 provided with horizontal lath 5^b, spaced apart as usual in the manner of laying lath. Between the lath 5^a and 5^b a dead air space A will be formed and in the space between the lath 5 and 5^a the concrete to form the 80 wall is formed, resting upon a suitable foundation F, as indicated in Figure 2 and in which the floor joists 7 may be mounted. At the corner of the structure the studs 2 may be placed back to back, as indicated at 85 8, and then the other wall running at right angles may be formed in a similar manner. The inside finish plaster will be applied to the lath 5 and the outside stucco will be applied to the lath 5^b, thereby completing the 90 interior and exterior of the wall.

From the foregoing description it will be noted that the form into which the concrete is poured is not removed, as usual in concrete structures, but remains as a framework or 95 skeleton enclosing the concrete and providing suitable air spaces in the wall and suitable means to which the finish plaster on the inside and the exterior stucco may be secured. I do not propose to utilize high 100 grade lumber in this form, as it is not necessary as a mold for the wall, it being merely sufficient to support the concrete until it becomes set and then the concrete supports the skeleton frame.

The width of the air space and the relative location of the studding may, of course, be varied according to the height of the building and the character of the climate where the structure may be erected.

In Figure 3 I have shown a modified construction which consists in providing

upright studding 9 on the inner lath and then providing another layer of lath 9^a to which the inside finish plaster is secured. A double air space is thus formed in the skeleton frame between which the concrete is poured.

In Figure 4 I have shown upright angle bars 10 arranged at suitable intervals on the inner side of the wall and channel bars 11 opposite the angle bars on the outer side of the mold or frame. These angles and channels are preferably pressed or rolled from thin sheet metal and will have no particular function of supporting the concrete, as the reinforcing metal would, but are merely intended as a support for the metal lath between which the concrete is allowed to run. These angle bars 10 have lugs 12 pressed therefrom, provided with holes 13 therein and the wire or expanded metal lath 14 is placed against the angle bars with the lugs inserted through the meshes or slots of the lath and the lath is then locked on the lugs by the insertion of small wire rods 15 through the holes. Corresponding lugs 12^a are pressed from the channels 11 and adapted to enter the meshes of the fabric or the slots of the expanded metal for locking the plates or sheets against the upright channels. The channels and angle bars are held in parallel relation by the cross slats 16 secured thereto at intervals and embedded in the concrete when it is poured between the outer and inner plates of the lath. A dead air space 17 is formed between the lath, secured to the inner face of the channels and the corresponding lath on the outer face, and whenever necessary, sheets of building paper may be interposed between the angles and channels and the lath for holding the concrete until it becomes set.

In Figure 6 the details of one way of mounting the metal lath on the supporting bars is shown and in Figure 7, instead of providing lugs pressed from the bars with holes therein to receive the locking wires, I bend the lugs to the position indicated at 18 where they press on the metal lath or fabric to lock it securely in place so that the plaster coat can be easily and quickly applied.

This structure is substantially the same as described with reference to Figures 1, 2 and 3, except that light metal is used in place of wood and the lath is composed of fabric or expanded metal or any of the well-known conventional metal lath instead of the wooden strips or slats shown and described with reference to sheet 1. I may provide a dead air space on each side of the concrete wall where the metal frame work is used, as illustrated in Figure 3 of the wooden construction. This, however, would merely amount to anchoring the additional angle or channel bars to the inner bars of the skeleton frame and then placing sheets of fabric or expanded metal thereon.

I claim as my invention:

1. A building wall comprising inner and outer groups of upright members arranged in parallel relation and having cross bars secured to the opposite members of said groups, lath secured to the outer and inner faces of one of said group of upright members, lath secured to the inner faces of the other group of members and forming with the first lath a space for pouring concrete therein, and the lath secured to the inner members and the outer faces of the outer members being adapted for receiving finish coats in plastic form.

2. A building wall comprising inner and outer wooden uprights arranged in pairs in parallel relation and spaced apart, tie bars secured at their ends to the opposite uprights, lath secured horizontally to the inner and outer faces of one group of uprights, and to the outer faces of the other group of uprights said lath co-operating with said uprights and said cross bars to form a skeleton frame, a dead air space being provided between the lath on the inner and outer faces of one group of uprights and the space between the groups of uprights being filled with a material in plastic form, a finish coat in plastic form applied to the outer lath of one group of uprights, and a second interior finish coat applied to the lath of the other group of uprights.

In witness whereof, I have hereunto set my hand this 26th day of January 1920.

SENECA H. TROMANHAUSER.
